DESIGN FOR A BOTTLE OR SIMILAR ARTICLE

James O. Billups, Manhattan Beach, Calif.

Application November 6, 1945, Serial No. 123,495

Term of patent 14 years

(Cl. D58—6)

To all whom it may concern:

Be it known that I, James O. Billups, a citizen of the United States, residing in Manhattan Beach, in the county of Los Angeles, State of California, have invented a new, original, and ornamental Design for a Bottle or Similar Article, of which the following is a specification, reference being had to the accompanying drawing, forming a part thereof.

The characteristic feature of my design resides in the form of an elongated recess in the wall of the bottle and a vertical handle element.

I claim:

The ornamental design for a bottle or similar article, as shown and described.

JAMES O. BILLUPS.
